United States Patent Office.

D. W. GLASSIE, OF NASHVILLE, TENNESSEE.

Letters Patent No. 96,795, dated November 16, 1869.

IMPROVED SEWING-MACHINE FAN.

The Schedule referred to in these Letters Patent and making part of the same.

To all whom it may concern:

Be it known that I, D. W. GLASSIE, of Nashville, in the county of Davidson, and State of Tennessee, have invented a new and improved Fan; and I do hereby declare that the following is a full, clear, and exact description of the construction and operation of the same, reference being had to the accompanying drawings, forming part of this specification.

My invention relates to a device which may be attached to the balance-wheel of a sewing-machine, or in any suitable manner to an actuating-wheel driven by any convenient power, and is provided with fans, which may be caused simply to rotate, or to have a compound motion, reciprocating and rotary.

The invention consists in the combination of mechanical means for operating the fans, which will be more particularly specified hereafter.

The same letters represent corresponding parts in the figures of the drawing.

A, Figure 1, is a large pulley, grooved on its periphery, and attached by screw-shanked hooks, B, to the balance-wheel of a sewing-machine, as illustrated in fig. 1.

D is an auxiliary pulley, which receives motion by a strap from A, and drives the fan-mechanism.

C is a suitable bed, with flanges *ff*, whereby the device may be attached to a table, bench, or other article.

cc are pillow-blocks, in which are located the bearings of the shaft E, of the said pulley D.

On the right-hand end of said shaft is placed a bevel-gear, F, which has a stud, *h*, on its plain side.

The upright shaft G passes through a curved support, H, and turns on a bearing in the bed C.

On the lower end of this shaft is a bevel-wheel, I, which gears in the bevel F, and is rotated by it.

The wheel I is sustained in gear with F by a mov-

able shoulder, whereby it may be let down and allowed to rest on the bed C.

The wheel F is also movable, and is taken off and reversed on its shaft, for a purpose hereafter mentioned.

J J represent fans, which are placed upon the top of shaft, and are rotated by the shaft G, which revolves them in a horizontal plane.

Figure 2 represents a pitman, O, attached to a pin, *h*, on the plain side of the bevel-wheel F, which has been reversed on its shaft E, and disconnected from the wheel I. At its upper end it is attached to the fan L, which swings loosely on a pin, 2.

As the crank O is reciprocated, by the rotation of the wheel F, it vibrates the fan L in a vertical plane.

With this apparatus a lady can operate the sewing-machine and fan herself simultaneously, without being sensible of the greater exertion of power which she is required to make.

Having now described all that is necessary to make my device understood,

What I esteem as of my invention, and desire to protect by Letters Patent, is—

1. The combination of a pulley, A, attached to the balance-wheel of a sewing-machine, with pulley D, shaft E, bed C *cc*, bevel-gears F I, support H, and shaft G, all arranged to operate a fan, J J, in the manner described.

2. The combination of said pulleys A and D, located as described; with the bevel F, reversed, the crank O, crank-pin *h*, supporting-shaft G, all arranged to swing the fan L on its pivot in a vertical plane, as shown and described.

D. W. GLASSIE.
